UNITED STATES PATENT OFFICE.

DAVID H. DURSTON, OF WEEDSPORT, NEW YORK.

DESIGN FOR A PRICE-LIST STANDARD.

SPECIFICATION forming part of Design No. 26,308, dated November 17, 1896.

Application filed July 18, 1896. Serial No. 599,741. Term of patent 7 years.

To all whom it may concern:

Be it known that I, DAVID H. DURSTON, of Weedsport, in the county of Cayuga, in the State of New York, have invented a new and useful Design in Price-List Standards, of which the following, taken in connection with the accompanying drawings, is a full, clear, and exact description.

Figure 1 is a front view of my design price-list standard complete. Fig. 2 is a cross-section thereof.

The leading feature of my design consists in a price-list standard as a unitary article, the whole when viewed presenting a pleasing effect upon the eye.

a is the standard, substantially rectangu-

lar in configuration, as shown, having a base *b* and beads *c d*, mounted upon one side a short distance apart, and a bead *e* upon the opposite edge.

f are rectangular compartments having their ends *g* semicircular in form.

What I claim is—

A price-list standard substantially as herein described and shown.

In witness whereof I have hereunto set my hand this 11th day of July, 1896.

DAVID H. DURSTON.

In presence of—

HOWARD P. DENISON,
C. W. SMITH.
